Application June 11, 1934, Serial No. 730,158

4 Claims. (Cl. 261—34)

This invention appertains to new and useful improvements in fuel vaporizers, and more particularly to a vaporizer of the type which can be readily connected to an internal combustion engine.

The principal object of the invention is to provide a vaporizer attachment for internal combustion engines wherein compressed air is utilized to break up the fuel sprayed from the float chamber, to the end that the fuel is finely vaporized before being admitted to the manifold.

Other important objects and advantages of the invention will become apparent to the reader of the following specification.

15 In the drawings:

Figure 1 represents an end elevational view of the device in accordance with the present invention.

Figure 2 represents a longitudinal sectional view through the mixing chamber.

Figure 3 represents a horizontal sectional view through the mixing chamber.

Figure 4 represents a vertical sectional view through the air pump.

25 Figure 5 represents a sectional view taken substantially on line 5—5 of Figure 3.

Referring to the drawings wherein like numerals designate like parts, it can be seen that numeral 5 represents a float chamber, while numeral 6 represents the induction tube or mixing chamber of the vaporizer, the same being provided with a flange 7 at one end, whereby the tube can be attached to the usual intake manifold. Reference numerals 8 and 8^a denote valves conventionally known as the choke and damper throttle which are rockably mounted in the induction tube 6. The tube, as is clearly shown in Figures 2 and 3, is provided with an elongated opening 9 in the wall thereof.

40 Numeral 10 represents a block which is suitably secured to the outer side of the tube 6 over the opening 9 and also suitably secured to the float chamber 5. This block 10 is provided with an elongated passageway 11 therein communicating at one end with the upstanding jet 12, while its opposite end is internally threaded to receive the plug 13. At this end of the passageway 11, the block 10 is provided with an upstanding neck 14 having a laterally disposed jet 15 which is adapted to flow across the tip of the fuel jet 16, these jets being arranged in substantially the manner shown clearly in Figure 3.

Reference numeral 17 denotes a compressed air pump having its inlet at 18 and the conduit pipe 19 extending therefrom to connect to the

block 10 and communicate with the passageway 11, as at 20.

Numeral 21 represents a baffle which is maintained spaced from the side portions of the tube 6 by the offset end portion 22 which is suitably secured to the side portions of the tube 6. This baffle serves to prevent heavy vapor from passing out of the tube 6. Any condensation is collected in the pocket 23, which is provided with a clean-out plug 24 and from this pocket, the liquid fuel can return to the float chamber by way of the conduit duct 25. (See Figure 3.) A conduit duct 27 also extends through the supporting arm 28 of the float chamber 5 and opens through the wall of the tube 6 at a point outwardly of the butterfly valve 8.

It can now be seen that in operation, let it be assumed that the motor 29 of the compressor or pump 17 is in circuit with the usual ignition switch of the automobile. When the switch is turned on, the motor 29 will become energized and drive the pump 17. Compressed air will now be supplied to the passageway 11 and will spray into the tube 6. Compressed air from the jet 15 in passing over the jet 16, will break up the fuel issuing from the jet 16 and thoroughly mix the same, while a second treatment of the fuel vapor is performed by the jet 12 spraying compressed air transversely of the tube 6, thus insuring complete mixing of the fuel vapor before it passes to the outlet end of the tube 6.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

1. A fuel vaporizer comprising a float chamber, a single air induction tube constituting a mixing chamber having one end open and the other end adapted for connection to an intake manifold of an internal combustion engine, a throttle valve and a choke valve mounted in the tube and axially spaced from each other to provide a vaporizing compartment in an intermediate portion of the tube, a fuel conductor leading from the float chamber and terminating in the vaporizing compartment in a fuel jet discharging a fuel stream at right angles to the axis of the tube, one of the air nozzles discharging air under pressure at the mouth of the fuel jet at right angles to the fuel stream, and the other of said air nozzles discharging air under pressure at an angle to the 55

air stream discharged by the first mentioned air nozzle.

2. A fuel vaporizer comprising a float chamber, a single air induction tube constituting a mixing chamber having one end open and the other end adapted for connection to an intake manifold of an internal combustion engine, a throttle valve and a choke valve mounted in the tube and axially spaced from each other to provide a vaporizing compartment of substantially the same diameter as the tube, a fuel conductor leading from the float chamber and terminating in the vaporizing compartment in a fuel jet discharging a fuel stream at right angles to the axis of the tube, a pair of air nozzles one to each side of the fuel jet, one of the air nozzles discharging air under pressure at the mouth of the fuel jet at right angles to the fuel stream and the other of said air nozzles discharging air under pressure at right angles to the air stream discharged by the first mentioned air nozzle, and a baffle in the vaporizing compartment, said tube being formed with a passage adjacent to the baffle and connected with the float chamber for conducting condensed fuel back into the float chamber.
3. A fuel vaporizer comprising a single elongated air induction casing constituting a mixing chamber having one open end and the other end adapted for connection to an intake manifold of an internal combustion engine, a throttle valve and a choke valve mounted in the casing and longitudinally spaced from each other to

provide a vaporizing compartment within the confines of the induction casing, a fuel jet and a pair of air nozzles all within the vaporizing compartment, one of said nozzles directed at the mouth of the fuel jet to produce a Venturi effect on the fuel jet, and the other of said nozzles directed at an angle to the air stream of the first mentioned nozzle to thoroughly mix the charge. 5

4. A fuel vaporizer comprising a float chamber, an air induction casing constituting a mixing chamber having one end open and the other end adapted for connection to an intake manifold of an internal combustion engine, a throttle valve and a choke valve mounted in the casing in spaced relation to each other to provide a vaporizing compartment within the confines of the induction casing, a fuel jet and a pair of air nozzles all within the vaporizing compartment, one of said nozzles directed at the mouth of the fuel jet, the other of said nozzles directed at an angle 10 to the air stream of the first mentioned nozzle, a baffle in the vaporizing compartment, said casing formed with a passage adjacent to the baffle and connected with the float chamber for conducting condensed fuel back into the float chamber, 20 and said casing formed with another passage connected with the float chamber at one end and registering at the other end with the mixing chamber between the open end of the casing and the vaporizing compartment. 25
